UNITED STATES PATENT OFFICE.

J. B. JOHNSON, OF BOSTON, MASSACHUSETTS, ASSIGNOR TO JNO. SPARROW, OF PORTLAND, MAINE.

PUMP.

Specification of Letters Patent No. 30,825, dated December 4, 1860.

To all whom it may concern:

Be it known that I, JAMES B. JOHNSON, of Boston, in the county of Suffolk and State of Massachusetts, have invented certain new and useful Improvements in Pumps; and I do hereby declare that the following is a full, clear, and exact description of the same, reference being had to the accompanying drawings, forming part of this specification, 10 in which—

Figure 1, is a longitudinal elevation partly in section, of a steam pump constructed according to my invention. Fig. 2, is a plan view of the same, and Fig. 3, is a 15 transverse section taken in the plane indicated by the line α , α , in Fig. 1.

Similar letters of reference indicate corresponding parts in the several figures.

My invention is more particularly applicable to steam pumps for steam fire engines, 20 and other purposes, but is also applicable to pumps worked otherwise than by steam power.

To enable others skilled in the art to make 25 and use my invention, I will proceed to describe its construction and operation:

A, is the reciprocating barrel bored internally and turned externally of cylindrical form and fitted to work within the 30 two stationary abutments D, D', which separate the inlet chamber F, and the outlet chamber G, of the pump, said abutments being bored out truly in line with each other, that the barrel A, may work freely within 35 the two. The abutments and the inlet and outlet chambers, may be made of a suitable casting suitably cored out. The inlet chamber consists of a cylindrical cavity larger than the exterior of the pump barrel, formed 40 between the abutments and has the inlet pipe f, at the bottom, and the outlet chamber consists of two annular cavities surrounding the abutments, and connected by a hollow chest on the top of which is arranged 45 the outlet pipe G', and the larger air vessel H within which is arranged the smaller air vessel N, of the inlet chamber. The abutment D', is closed, by a movable head a, and the other one D, through which 50 the barrel A, projects some distance is fur-

nished with a stuffing box I, to prevent the escape of water round the barrel. In each abutment there is a port e, which may extend all round it, or instead of such continuous ports, two series of ports as shown 55 in Fig. 3; and in the barrel A, there are two series of ports B, B, each of which series extends nearly all around, having only sufficient metal left between the several ports to keep the barrel entire, the two series being at such distance apart, less than the distance between the ports e, of the abutments that either series may be brought into communication with the abutment port e, at its own end of the pump, while the other series 60 communicates with the inlet chamber F. The barrel A, it will be understood by reference to Fig. 1, combines with the abutments to separate the inlet chambers, from the discharge chamber, and the only communication between the said chambers is through the ports B, and e, and through the interior of the barrel.

P, is the piston or plunger fitted to the barrel A, and having its rod p, passing 75 through the stationary head J, which is fitted like a piston to the interior of the barrel to close the outer end thereof, and which is furnished outside of the barrel with a stuffing box q, to prevent the escape 80 of water round the rod. This head is held in place by two rods O, O, which connect it with the steam cylinder Y, or with any stationary part of the apparatus outside of 85 the pump.

The plunger rod p, constitutes also the rod of the piston of the steam cylinder Y, by which the pump is driven and is furnished with a crop head Y', which is fitted to work on the stationary guide rods S, S, 90 which connect the pump casing with the steam cylinder. The said crop head is also connected by two connecting rods 6, 6, with two crank pins T, T, carried by two fly wheels I, I, on a shaft C, which works in 95 bearings at the back of the steam cylinder, said shaft having its axis transverse to, but in the same plane with the axis of the piston rod, and deriving a rotary motion from the piston rod through the connecting rods 100

and cranks. The fly wheels are made much heavier on the opposite side of their axis to that on which the cranks are arranged, and they are arranged at equal distances from 5 opposite sides of a plane passing through the axis of the plunger and barrel. The barrel A, is furnished with a crop head K, working on the aforesaid guides S, S, and this crop head is connected by two rods M', 10 M', with two eccentrics M, on the main shaft, such eccentrics being set a little more than 90° in advance of the cranks T, T, and having such a throw as to give the barrel a reciprocating movement, of such length as 15 to bring each series of ports B, B, of the barrel in turn into communication with its respective port e, in the abutment. The length of stroke of the plunger P, is such that it will just arrive at, or nearly at the 20 edges of the abutments G, G. The cross head K, of the barrel A, carries the rod R, which works the slide valve of the cylinder. The operation is as follows. The shaft C, 25 having rotary motion imparted to it, either by the steam piston as before described or by other means, the plunger P, and barrel A, have each a separate and independent reciprocating motion imparted to them, the movement of the barrel in either direction, 30 commencing just before the plunger has completed half its stroke. Fig. 1 represents the plunger as moving in the direction of the arrow marked upon it, having nearly made half stroke, and the barrel having just completed its stroke in the opposite direction and commencing its return with the plunger. The water is now flowing from the inlet or 35 suction chamber F, through the ports B, at the left hand, end of the barrel into the barrel, following the plunger, and it is being forced from before the plunger through the ports B and e, at the other end into the discharge chamber G. When the plunger shall have completed its stroke, the barrel A, 40 will have made a little more than half-stroke, and the distance between the outer or furthest edges of the two series of ports B, B, being a little greater than the distance between the inner or nearest 45 edges of the two ports, or series of ports e, e, there will be communication between the barrel, and the discharge chamber on each side of the plunger, and the latter will "pass its center" or in other words 50 will have the direction of its motion changed, while in equilibrio, but yet the water is no case permitted to flow back into the inlet chamber as the ports B, B, are intended to be not quite so wide as the portions of the 55 abutments between the ports e, e, and the inlet chamber. As the barrel continues its motion forward, now moving in the opposite direction to the plunger, it opens communication between the inlet-chamber and

the barrel at the right hand side of the plunger, and enlarges the communication between the barrel and the outlet chamber on the opposite side of the plunger. It will be thus understood that when the plunger is at half stroke, and moving at its greatest speed 65 the barrel is in position to give the greatest opening to the inlet chamber behind the plunger, and to the discharge chamber in front of the plunger, and not only this but it (the barrel) is at that time working at its 70 slowest speed, and so preserves nearly the full opening during that part of the stroke of the plunger in which it suffers but little diminution of velocity. The opening of the ports is in fact at all times in proportion to 75 the velocity of the plunger, and as the barrel A, works in equilibrio, both within the inlet chamber and discharge chamber, and the direction of the movement of the plunger changes while it is in equilibrio, the movements of the pump are easy and the flow of water through it free, and hence it may be worked at a much higher velocity than 80 pumps with flat slide valves or valves working 85 from and to their seats. 90

By the arrangement of the smaller air vessel N, of the inlet chamber F, within the larger air vessel H, of the discharge chamber G, it is brought directly over the chamber F, and hence it will compensate promptly 95 for any change of velocity in the water flowing into and out of the said chamber and into the pump barrel A, and by the arrangement of the fly wheels as described, with their heaviest sides opposite to the main 100 crank pins, the effect of the motion of the water in the pump, and the momentum of the working parts are counterbalanced, and hence longitudinal oscillation is prevented; and by arranging one fly wheel on each side 105 of, and at equal distances from the axis of the plunger and barrel all lateral oscillation is prevented, and by these means combined the pump is made to possess special advantages for steam fire engines, and for any 110 other purpose in which an easy and steady motion is required. 110

What I claim as my invention and desire to secure by Letters Patent is—

1. Having the outside cylinder divided 115 into three compartments G, G, F, (separated by the abutments D, D',) which entirely surround the moving barrel A, as shown and described so that said cylinder A, will work in equilibrio. 120

2. The extension of the moving barrel A, beyond its outer cylinder so that said cylinder may be operated by the application of proper force to said exterior end all as herein shown and described. 125

3. The arrangement of the chamber N, directly over the suction chamber F, so as to conduct the water in a direct line to the

vacuum chamber all as herein shown and described.

4. The combination of the barrel A, with the valve rod R, as herein shown and described so that the same eccentric that drives the slide valve will also operate the barrel A, all as set forth.
5. The employment within the moving

barrel of the stationary piston head J, when constructed and operating as and for the purpose herein shown and described.

J. B. JOHNSON.
